UNITED STATES PATENT OFFICE.

CHARLES J. DAVIDSON, OF MILWAUKEE, WISCONSIN.

WATER-LEVEL REGULATOR.

Application filed January 27, 1923. Serial No. 615,413.

To all whom it may concern:

Be it known that I, CHARLES J. DAVIDSON, a citizen of the United States, and resident of Milwaukee, in the county of Milwaukee, 5 and State of Wisconsin, have invented new and useful Improvements in Water-Level Regulators, of which the following is a description, reference being had to the accompanying drawings, which are a part of this 10 specification.

This invention relates to water level regulating mechanisms for boilers, and has for one of its objects to provide a device of this character employing solid or non-collapsible 15 floats for controlling the admission of water to steam or other boilers, whereby the water level therein may be automatically maintained substantially constant.

Devices of this character now in general 20 use are commonly provided with floats of hollow construction which often lose their buoyancy, due to leaks in the walls of the floats permitting the entrance of fluid therein, with the result that the regulators 25 do not function properly and in many instances boilers are seriously injured due to low water. In some cases the boilers explode inflicting a great deal of damage and 30 possibly loss of life.

It is therefore the principal object of this 35 invention to provide a water level regulator employing metal floats or other controlling means which are solid in construction, to the end that, so far as is humanly possible, the 40 danger of leaks occurring therein, with the resulting disastrous consequences, may be obviated.

A further object of the invention is to 45 provide a regulator which may be readily attached to boilers which are already in use, or to new boilers, and which will be simple in construction, comparatively inexpensive to manufacture, and more efficient in action than those which have been heretofore proposed.

A still further object of the invention is to 50 provide a regulating device of the class described having associated with it an efficient alarm mechanism, adapted to give notice in the event of the failure of the regulator to function properly.

With the above and other objects in view, which will appear as the description proceeds, the invention consists in the novel details of construction and combinations of 55 parts more fully hereinafter disclosed and

particularly pointed out in the appended claims.

In the accompanying drawings in which like numerals designate like parts in all the 60 views;

Figure 1 is a central vertical sectional view of a regulating mechanism and its associated alarm, made in accordance with the 65 present invention;

Fig. 2 is a diagrammatic development of the valve casing illustrating the port openings therein;

Fig. 3 is a view similar to Fig. 2 of the 70 valve itself;

Fig. 4 is a horizontal sectional view, taken approximately on the plane indicated by the line 4—4 of Fig. 1, looking down;

Fig. 5 is a fragmentary vertical sectional view through the upper portion of the 75 mechanism, at right angles to Fig. 1, and taken approximately on the plane indicated by the line 5—5 of the said figure; and,

Fig. 6 is a horizontal cross-sectional view 80 through the inlet and outlet ports and the valve, taken approximately on the plane indicated by the line 6—6 of Fig. 1, looking down.

Referring to the said drawings, the numeral 10 indicates a casing of any suitable 85 construction, which may be provided with the substantially hemi-spherical cap member 11, which closes the top of the said casing, while the lower portion of the latter is adapted to be secured to the valve housing 90 12. Suitably journaled in the upper cap member 11 is a transverse shaft 13, upon which is rotatably mounted a pair of 95 sprocket wheels 14 and 15. The said sprocket wheels may be mounted upon anti-friction bearings 16, see Fig. 5, and they are each provided with reduced hub portions 17 and 18 respectively, having sprocket teeth 19 and 20, as will be clear from Figs. 1, 4 and 5.

Housed within the casing 10 is a pair of 100 metal float or control members, 21 and 22, which are of such dimensions as to freely slide therein, and these said members are supported within the said casing by means 105 of chains 23 passing over the sprockets 14 and 15, and chains 24 passing over the sprockets 19 and 20. One end of each of the chains 23 is secured to the upper surface of the float or control member 21, 110 while the other ends of the said chains are suitably secured to the said sprockets 14

and 15. In like manner, one end of each of the chains 24 is secured to the upper float member 21, and the other ends of the said chains are secured to the sprockets 19 and 20.

As above mentioned, the sprockets 19 and 20 are formed on the reduced hub portions 17 and 18 of the sprocket wheels 14 and 15 respectively. As illustrated in the drawings, the sprockets 19 and 20 are approximately one half the diameter of the sprockets 14 and 15, and it thus results that whenever the float member 22 moves upwardly or downwardly, the float member 21 will move in an opposite direction, at approximately one half the speed and to one half the distance travelled by the said member 22.

Rigidly secured to the upper float member 21 is a valve rod 25, which passes through the central opening or bore 26 in the float member 22, and carries on its lower end valve members 27 and 28.

The said valve members 27 and 28 preferably take the form of hollow cylinders having one end open, as clearly shown in Fig. 1, and the lowermost member 28 is provided with a plurality of angularly disposed ports or openings 29, arranged in the side walls. These said ports or openings are preferably of different dimensions, as clearly indicated, and they are adapted to co-act with similar ports or openings 30, provided within the walls of a sleeve member 31, rigidly supported within the valve casing 12, in any suitable manner.

This said sleeve passes through an annular chamber 32, formed within the valve casing 12, which is adapted to communicate with the interior of the said sleeve through a plurality of apertures or openings 33, provided within the walls of the sleeve. The upper portion of the sleeve is further provided with a series of ports or openings 34, of various lengths, which are adapted to co-operate with the upper valve member 27, all as will appear more fully below.

The valve casing 12 is provided with an inlet opening 35 leading into the chamber 32, and an outlet passage 36 leading from the interior of the said casing, as will be clear from Fig. 1, whereby feed water from any suitable source of supply, not shown, may be introduced into the boiler from the passage 36. The said casing or housing 10 is also provided with the passages 37 and 38, connected to the boiler, whereby the water within the latter may find its way into the interior of the said casing 10. The said casing is further provided with the usual sight glass or tube 39 having communication through the angular valves 40 and 41 with the interior of the casing 10, in order that the level of the water within the

casing and the boiler may be observed in the said glass.

In order to sound an audible alarm, should the control mechanism, for any reason, fail to function properly, and the water level rise above or fall below the danger point, there is provided a whistle 42, which is threaded into the upper cap member 10, as at 43, see Fig. 1. This said alarm or whistle is provided with a controlling valve 75 which is adapted to be actuated by either of two bell crank levers, 44 or 45, which levers are adapted to be struck by either of the pins, 46 or 47, carried by the sprocket wheels, 14 and 15 respectively, when the latter are revolved by their controlling float members, 21 and 22.

The operation of the improved regulator is as follows:—Under the well known laws of physics a solid body which is immersed within a liquid is buoyed up with a force equal to the weight of the liquid which it displaces. In the present invention advantage is taken of this fact in that the controlling member 22 is partly immersed in 90 and buoyed up by the water within the casing 10, which is in communication with the boiler. Supposing the float or controlling member 22 to weigh two pounds in air and to be of such dimensions as to displace one pound when so immersed in water. Now if the float or controlling member 21 weighed one pound and the two members were suspended in the manner above disclosed by means of the chains, 23 and 24, 100 on sprockets of the same size, when the lower member 22 was immersed in the water to displace one pound thereof a balance would exist so that there would be no relative movement of the members, 21 and 22. 105 But since the sprockets 19 and 20 are only approximately one half the diameter of the sprockets 14 and 15, the member 21 is acting with a leverage only half as great as that of the member 22, and its weight must therefore be increased proportionately to effect the balance sought.

Should the water level within the casing 10 fall so as to reduce the amount of water displaced by the lower member 22, the buoyant effect of the water upon the said member will be lessened with the result that the balance will be destroyed and the said member 22 will descend, thereby raising the upper member 21 to a distance and at a speed approximately one half that travelled by the member 22, due to the differential obtained by using the different sized sprockets 14, 15 and 19 and 20. Such movement of the upper member 21 will carry with it the valve stem 25, together with the valve members, 27 and 28, thereby bringing the ports or openings 29 of the lower valve member 28 into register with the ports or openings 30 of the valve sleeve 31, and furthermore 130

causing the lower end of the upper valve member 27 to uncover a portion of the ports or openings 34 of the sleeve 31. Feed water entering the inlet passage 35 of the valve casing 12 has filled the chamber 32, passed through the openings 33 in the sleeve 31 and filled the interior of the said sleeve. When the sleeve ports 30 and 34 are opened, as just disclosed, this feed water will pass through the said ports into the outer chamber 50, and from thence by way of the passage 36, into the boiler.

As the water level within the boiler rises as a result of this admission of feed water, the level within the casing 10 will rise correspondingly, thus increasing the buoyant effect upon the lower controlling member 22, so that the upper member 21 will overbalance the same, whereupon the said upper member will descend and the lower member rise, at the same differential rates thereby cutting off the supply of feed water by means of the valve members, 27 and 28, as will be readily apparent.

25 During the rising or falling movements of the members, 21 and 22, the sprocket wheels, 14 and 15, are revolved in one direction or the other, and should the water level within the boiler rise above or fall below the danger point, one of the pins, 43 or 47, will be brought into engagement with one or the other of the bell crank levers, 44 or 45, thereby opening the valve controlling the whistle or alarm 42, and permitting steam from the boiler, which has entered the casing 10 through the passage 37, to enter the said whistle and cause the same to sound an audible alarm.

The valve casing 12 may also be provided with a suitable manually controlled valve 51, controlling communication between the chamber 32 and the chamber 50 directly, whereby feed water from the passage 35 may be supplied directly to the passage 36 without passing through the automatically controlled valves, 27 and 28.

It will thus be seen that this invention provides an automatic control and a high and low water level alarm, in which it is not necessary to employ hollow float members, which are liable to become disarranged through leaks and the like. It results that the device is positive and automatic in its action and is not likely to get out of order, thus endangering the boiler or the lives of the attendants.

While one specific embodiment of the invention has been illustrated and described, it is obvious that those skilled in the art may vary the details of construction as well as the arrangement of parts without departing from the spirit of the invention, and therefore it is not wished to be limited to the above disclosure except as may be required by the accompanying claims.

What is claimed is:

1. An automatic liquid level control mechanism comprising a chamber in which the liquid level may rise and fall; a substantially solid metal control member within said chamber adapted to displace and be buoyed up by said liquid; a substantially solid metal counterbalancing member; differential connections between said members whereby they may move in opposite directions relative to one another in response to the rise and fall of said liquid level; and a valve carried by one of said members for directly controlling the admission of feed liquid, to maintain said level substantially constant. 70

2. In a liquid level control and alarm device for boilers, a chamber in which the water level may rise and fall; a substantially solid metal member within said chamber adapted to displace and be buoyed up by the water therein; a substantially solid metal counterbalancing member within said chamber; non-rigid differential connections between said members, whereby they may move in opposite directions relative to one another in response to the rise and fall of said water level; a valve casing associated with said chamber; a valve stem carried by one of said members; and a valve carried by said stem within said casing, for controlling the passage of feed water therethrough to maintain said water level substantially constant. 85

3. In a liquid level control and alarm device for boilers, a chamber in which the water level may rise and fall; a substantially solid metal member within said chamber adapted to displace and be buoyed up by the water therein; a substantially solid metal counterbalancing member within said chamber; chain and sprocket connections between said members, whereby they may move in opposite directions relative to one another at different rates of speed in response to the rise and fall of said water level; a valve casing associated with said chamber; a valve stem carried by one of said members; a valve carried by said stem within said casing, for controlling the passage of feed water therethrough to maintain said water level substantially constant; an audible alarm device associated with said chamber; and means carried by said chain and sprocket connections for actuating said alarm. 100

4. In a water level control and alarm device for boilers, a substantially closed chamber communicating with said boiler in which the water level may rise and fall; sprocket wheels rotatably mounted in said chamber; chains passing over and each having an end secured to one of said wheels; a substantially solid metal control member within said chamber, adapted to displace and be buoyed 115

125

130

up by the water therein, said member being connected to the other end of certain of said chains; a substantially solid metal counterbalancing member, connected to the other 5 end of the others of said chains, above said first member; and a valve controlled by the movements of said members, adapted to control the admission of feed water to said boiler, whereby said water level may be maintained substantially constant.

5. In a water level control and alarm device for boilers, a substantially closed chamber communicating with said boiler in which the water level may rise and fall; pairs of 15 different sized sprocket wheels rotatably mounted in said chamber; chains passing over and each having an end secured to one of said wheels; a substantially solid metal control member within said chamber, adapted 20 to displace and be buoyed up by the water therein, said member being connected to one end of the chains associated with the larger sprockets; a substantially solid metal counterbalancing member, connected to the other 25 end of the chains associated with the smaller sprockets, above said first member; and a valve controlled by the movements of said members, adapted to control the admission 30 of feed water to said boiler, whereby said water level may be maintained substantially constant.

6. In a water level control and alarm device for boilers, a substantially closed chamber communicating with said boiler in which the water level may rise and fall; sprocket 35 wheels rotatably mounted in said chamber; chains passing over and secured to said wheels; a substantially solid metal control member within said chamber, adapted to 40 displace and be buoyed up by the water therein, said member being connected to one

end of certain of said chains; a substantially solid metal counterbalancing member connected to one end of the others of said chains, above said first member; a valve carried by said counterbalancing member and controlled by the movements of said members, adapted to control the admission of feed water to said boiler, whereby said water level may be maintained substantially 50 constant; an audible alarm device communicating with said chamber and provided with a valve; and means comprising pins carried by said sprocket wheels for actuating said last named valve to sound the alarm.

7. In a water level control and alarm device for boilers, a substantially closed chamber communicating with said boiler in which the water level may rise and fall; pairs of different sized sprocket wheels rotatably 60 mounted in said chamber; chains passing over and each having an end secured to one of said wheels; a substantially solid metal control member within said chamber, adapted 65 to displace and be buoyed up by the water therein, said member being connected to one end of the chains associated with the larger sprockets; a substantially solid metal counterbalancing member, connected to the other 70 end of the chains, associated with the smaller sprockets above said first member; a valve controlled by the movements of said members, adapted to control the admission 75 of feed water to said boiler, whereby said water level may be maintained substantially constant; an audible alarm device communicating with said chamber and provided with a valve; and means comprising pins carried by said sprocket wheels for actuating said last named valve to sound the alarm.

In testimony whereof, I affix my signature.
CHARLES J. DAVIDSON.
